RELIGIOUS CROSS

Delphus Goudreau, % Mother-of-Pearl Cross Co.,
Northbridge, Mass.

Filed Feb. 4, 1963, Ser. No. 73,428

Term of patent 14 years

(Cl. D29—23)

FIG. 1 is a view in front elevation of a religious cross showing my new design, and

FIG. 2 is a view in side elevation thereof, looking in the direction of arrow 2 in FIG. 1.

The rear surface is plain.

I claim:

The ornamental design for a religious cross as shown and described.
